Primary Examiner — Kevin K Rudzinski*Assistant Examiner* — Amber J Rabie*(74) Attorney, Agent, or Firm* — Hovey Williams LLP(57) **CLAIM**

The ornamental design for a connection device, as shown and described.

DESCRIPTION

FIG. 1 is a perspective view of a connection device embodying a first embodiment of our design;

FIG. 2 is a front elevation view of the connection device shown in FIG. 1, with the rear elevation view being an identical image;

FIG. 3 is a cross-sectional view of the connection device taken along line 3-3 in FIG. 2; and,

FIG. 4 is a side elevation view of the connection device shown in FIGS. 1-3, with the opposite side elevation view being an identical image.
